EDWARD E. STEVENSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

METHOD OF PLACING LINERS IN SLEEVES FOR DEEP-WELL OIL PUMPS

Application filed August 27, 1928. Serial No. 302,230.

My invention relates to oil well pumps, and particularly to a novel and improved pump barrel and method of assembling same.

5 In the oil producing industry, the oil is lifted to the surface of the ground by means of an oil well pump which consists of a barrel attached to the lower end of the pump tubing, and a pump plunger adapted to be reciprocated in the pump barrel by means of a string of sucker rods extending through the pump tubing and the surface of the ground. At the surface of the ground is a walking beam whereby a reciprocatory motion is imparted to the string of sucker rods for reciprocating the pump plunger.

The pump barrel ordinarily used consists of a jacket having collars secured to the opposite ends thereof. Inside the jacket is a plurality of liners which are accurately machined to form a true internal cylindrical surface. These liners ordinarily are made in short sections to facilitate true boring and grinding, and are placed in the jacket in end contact with each other, and also with their external faces in contact with the internal surface of the jacket.

It is one of the objects of my invention to provide a pump barrel consisting of a jacket and liners secured in the jacket, the liners not being in contact with the jacket. The object of this construction is that accurate machining of the exterior of the liners and the interior of the jacket is eliminated.

35 A further object of the invention is to provide a pump barrel in which one end of the jacket and one end of an end liner, which is located in the jacket, are provided with centralizing means for holding the liner in centralized position in the jacket, and in which the liners are clamped together so that the other of the liners are held in centralized position due to their being clamped between end liners of the pump barrel.

45 A further object of the invention is to provide in a pump of the character previously described an assembly of pump liners consisting of end and intermediate liners, the end liners having diametrically enlarged centralizing portions thereon, and a jacket for

holding said liners, this jacket having cylindrical inner wall surfaces near the ends thereof for receiving the diametrically enlarged portions of the end liners whereby to centralize such end liners within the jacket.

55 A still further object of the invention is to provide a method of assembling my unique pump barrel.

Other objects and advantages of the invention will be pointed out in the following 60 description.

Referring to the drawing in which a preferred pump barrel and method is illustrated,

Fig. 1 is a vertical section through the 65 pump barrel, embodying the features of the invention.

Fig. 2 is an enlarged vertical section of one end thereof.

Fig. 3 is a section taken on the line 3—3 70 of Fig. 2.

Fig. 4 is a sectional view illustrating one step in the process of assembling the pump barrel.

75 Referring to the drawing in detail, the numeral 11 represents the jacket of the pump barrel. This jacket is ordinarily formed of steel, and is of such character as to have considerable tensile strength, and to withstand considerable strains and jars. As 80 shown best in Fig. 2, the ends of the jacket 11 are provided with internal threads 12. At the inner ends of the internal threads 12 are centralizing recesses 14. The centralizing recesses 14 are concentric to the 85 axis of the jacket 11, and are accurately machined to a cylindrical form.

Enclosed by the jacket 11 is a plurality 90 of intermediate liners 15, and a pair of end liners 16. In very short barrels there may be only one intermediate liner 15, or there may be only the two end liners 16. Each of the liners is of such an external diameter that an annular space 17, which may be about $\frac{3}{16}$ of an inch, is provided between the liners 95 and the internal cylindrical face of the jacket 11. Each liner has an accurately bored bore 18, and these bores are aligned so as to provide a continuous cylindrical bore in which the plunger of the pump may reciprocate. 100

End faces 19 of each liner 15 and 16 are formed in a plane at right angles to the axis of each liner, and are held in contact with each other.

- 5 The outer end of each end liner 16 is provided with a centralizing shoulder 21. The centralizing shoulder 21 of each end liner 16 is provided with an accurately machined cylindrical surface 22, which is adapted to be a sliding fit with the cylindrical surface of the centralizing recesses 14. The shoulders 21, when resting in the centralizing recesses 14, retain the end liners 16 concentrically with the axis of the pump jacket 11.
- 10 15 The intermediate liners 15 are adapted to be clamped between the end liners 16 concentrically on the main axis of the pump jacket 11, as will be described.

Adapted to be screwed into the internal threads 12 formed in the opposite ends of the pump jacket 11 are end collars 24. The end collars 24 are provided with external threads 25, which are advanced into the ends of the pump jacket 11 in contact with 20 the internal threads 12. The inner ends of the collars 24 are provided with accurately machined end faces 26, which contact the accurately machined end faces 27 of the end liners 16. When the end collars 24 are secured to the pump jacket 11, as illustrated 25 in the drawing, the intermediate liners 15 and the end liners 16 are rigidly clamped together so that they are relatively immovable. The end collars 24 have openings 28 30 which connect to the bores 18 of the liners 15 and 16 and in the ends of the openings 28 are internal threads 29 so that the pump barrel may be attached to other parts of the oil pumping equipment.

35 40 Referring particularly to Fig. 4, I will now describe the method of assembling the pump barrel of my invention.

In the method of assembling, the liners 15 and 16 are first assembled on a mandrel 45 indicated by the numeral 35 in Fig. 4. This mandrel is preferably of the expanding type, and for this purpose I may use a mandrel similar to the one patented by Daniels and Burgess on March 21, 1911, Patent No. 50 987,347. Any other suitable mandrel, however, may be used. In the drawing the mandrel and parts are shown in vertical position. Ordinarily the assembling is done with the parts in horizontal position. Fig. 4 is 55 vertically arranged only to conserve space on the drawing. The purpose of placing the liners 15 and 16 on the mandrel 35 is to hold them in true axial alignment during the process of assembling.

60 65 All of the liners are placed on the mandrel, with the exception of one of the end liners 16. The assembly of the mandrel and liners is then inserted into the pump jacket 11 from one end thereof so that the centralizing shoulder 21 of the end liner carried by

the mandrel, rests in the centralizing recess 14. The other end liner is then placed on the mandrel from the opposite end of the jacket 11. It will be seen that this is necessary in view of the fact that the centralizing shoulder 21 would not permit an end liner to be inserted through the jacket. At this time all of the liners are on the mandrel 35, and the centralizing shoulders 21 of the two end liners 16 are positioned in the centralizing recess 14. The mandrel 35 at this time may be adjusted so that the liners will be held in true axial alignment.

The centralizing means, which consists of the centralizing shoulder 21 and the centralizing recess 14 holds the end liners 16 concentrically with the jacket 11, and the mandrel 35 holds the intermediate liners 15 in true axial alignment with the end liners 16. Therefore all of the liners are in true axial alignment with the axis of the jacket 11.

The next step in the process is to attach the end collars 24 to the jacket 11. The end collars 24 are screwed tightly against the end faces of the end liners 16 with the result that the intermediate liners and end liners 15 and 16 are rigidly clamped together so that it is absolutely impossible for them to move relative to each other. The mandrel 35 is then adjusted so that it may be moved from the liners, this constituting the final step in the assembling process.

The important feature of the invention, as emphasized in the first part of the specification, is that the liners 15 and 16 are spaced 100 from the jacket 11, the end liners being centralized in the jacket 11 by the centralizing means, and the intermediate liners 15 being centralized during the assembling of the pump barrel, and being thereafter held in 105 centralized position due to their being clamped between the end liners 16. This design is not only entirely satisfactory in operation, but has certain advantages over the ordinary pump barrel in which all of the 110 liners are in contact with the jacket.

One advantage is that because of the annular space 17, the internal face of the jacket 11 and the external faces of the intermediate liners and end liners 15 and 16 do not have 115 to be accurately machined. This conduces to economy.

Another advantage of the invention is that in the event that the jacket 11 becomes dented, the dent may be received by the space 17, and will not damage any of the liners in any manner.

The invention in its broad concept consists of a jacket, liners in the jacket, not in contact with the jacket, centralizing means at 125 the end of the pump barrel, and means for clamping the liners together.

Other features of the invention obviously reside in the details of construction of the preferred form of the invention illustrated 130

herein, but I do not intend to be limited to this specific embodiment of the invention.

I claim as my invention:

1. A pump barrel comprising: a jacket having internal threads formed in the ends, and a centralizing recess at the inner ends of said internal threads; an intermediate liner in said jacket, said intermediate liner being smaller in external diameter than the 10 internal diameter of said jacket; end liners in the ends of said jacket, said end liners engaging said intermediate liner and being of smaller external diameter than the internal diameter of said jacket; centralizing shoulders formed on said end liners, and rested in said centralizing recesses for centralizing said liners; and end collars screwed into said internal threads for clamping said liners together, said collars having inner end faces 20 perpendicular to the axis of said liners.

2. A pump barrel comprising: a jacket; liners in said jacket, there being an annular space in said jacket around said liners; centralizing means operating between the ends of 25 said jacket and the ends of the end liners of said liners, said centralizing means comprising a centralizing annular face formed in each end of said jacket and a centralizing face formed on said end liners for engaging 30 said annular faces; and separate clamping means exerting pressure against the outer end faces of said liners for clamping said liners together, the inner end faces of said clamping means being perpendicular to the axis of 35 said liners.

3. A pump barrel comprising: a jacket; liners in said jacket, there being an annular space in said jacket around said liners; centralizing means operating between the ends of 40 said jacket and the ends of the end liners of said liners, said centralizing means comprising a centralizing annular face formed in each end of said jacket and a centralizing shoulder formed on said end liners for engaging 45 said annular faces; and clamping means for exerting end pressure to clamp said liners together.

4. A pump barrel comprising: a jacket; liners in said jacket, there being an annular space in said jacket around said liners; centralizing means operating between the ends of 50 said jacket and the ends of the end liners of said liners, said centralizing means comprising a centralizing recess formed in said jacket and a centralizing shoulder formed on one of said liners and engaged in said centralizing recess; and clamping means exerting end pressure for clamping said liners together.

60 5. A method of assembling a pump barrel, comprising: assembling a plurality of liners on a mandrel so that their bores are in alignment; placing the liners in a jacket so that the walls of the liners and the walls of the 65 jacket are not in contact; centralizing the

ends of the liners by engagement with annular centralizing faces formed in the ends of the jacket; exerting end pressure to clamp the liners in the jacket; and removing the mandrel.

6. A pump barrel comprising: a jacket having axially aligned cylindrical internal faces near its ends; a plurality of liners in said jacket including end and intermediate liners, there being an annular space in said 70 jacket around said liners, said end liners having cylindrical enlargements thereon adapted to centralizing engagement with said cylindrical faces of said jacket; and means exerting end pressure against the outer ends 75 of said end liners for clamping said plurality of liners together.

In testimony whereof, I have hereunto set my hand at Los Angeles, California, this 18 day of August, 1928.

EDWARD E. STEVENSON.
